[57] CLAIM

The ornamental design for a wall-mounted drying rack, as shown and described.

DESCRIPTION

FIG. 1 is a top left front perspective view of a wall-mounted drying rack showing my new design;

FIG. 2 is a top plan view thereof;

FIG. 3 is a front elevational view thereof; the rear elevational view being a mirror image;

FIG. 4 is a left side elevational view thereof; the right side elevational view being a mirror image; and,

FIG. 5 is a bottom plan view thereof.

FIG. 1***FIG. 4****FIG. 2**FIG. 3**FIG. 5*
